UNITED STATES PATENT OFFICE

BENJAMIN F. CLARKE AND WILLIAM J. McDONALD, OF DES MOINES, IOWA

LUBRICATING BAR

Application filed August 19, 1929. Serial No. 386,864.

The object of this invention is to provide an improved construction for a tool in the nature of a pry bar which is particularly useful in the operation of lubricating vehicle 5 springs.

A further object of the invention is to provide an improved tool which is capable of being used in such manner as to relieve the pressure on the spring shackles and spring 10 suspension bolts in such manner that lubricant may be readily introduced to the parts which ordinarily receive the greatest pressure and the greatest amount of wear in use.

Still another object of the invention is to 15 provide an improved pry bar having an arcuate fulcrum member adjacent to one end to facilitate the operation of separating two yieldably connected members.

Another and further object of the invention 20 is to provide a tool of the class described which is simple and economical in construction and capable of use in a variety of ways and in many different positions for facilitating lubricating operations.

With these and other objects in view, our 25 invention consists in the construction, arrangement and combination of the various parts of our device, whereby the objects contemplated are attained, as hereinafter more 30 fully set forth, pointed out in our claims, and illustrated in the accompanying drawings, in which:

Figure 1 is a plan view of our improved 35 tool.

Figure 2 is a side elevation of the same.

Figure 3 is an elevation partly in section illustrating the method of using the tool with relation to vehicle spring constructions in which spring shackles are employed.

Figure 4 is an elevation showing the tool 40 in section and in position for use with a different type of spring construction wherein the spring is connected directly to a bolt carried by the horn of the frame member.

Figure 5 is a section on the line 5—5 of 45 Figure 4, showing the tool in elevation and in position for use.

Figure 6 is an elevation showing the tool 50 as employed for use with a still different type of spring construction in which the spring is

arranged transversely above the vehicle axle.

Figure 7 is a sectional elevation illustrating a modified form of tool in position for use with a vehicle construction having spring shackles and a bumper arranged close to the 55 end of the spring and frame member.

The tool or lubricating bar as shown includes a relatively straight body portion 10 which is flattened, slightly curved and attenuated at one end to form a blade 12. It will be noted from Figure 2 that the blade does not extend laterally beyond the longitudinal planes defining the side margins of the body 10.

At its opposite end portion the body is also flattened to form the shank 14 and this shank terminates in a curved hook portion 16 which extends substantially at right angles thereto and is attenuated at its end.

A fulcrum member 18 is formed or mounted on the shank 14. As shown in Figures 1 and 2, the fulcrum member is separately formed and is of channel shape and is secured to the shank 14 by rivets or the like 20.

The fulcrum member 18 preferably is of substantially right angled construction, having its longer leg extending along the shank 14 and its shorter leg extending therefrom at a point near the juncture of the shank and body 10. The hypotenuse of the fulcrum 55 member is formed on a convex arc and is designated by the numeral 18'. This arcuate surface is provided to permit a rolling or easy sliding contact with an object as hereinafter set forth.

We have illustrated several different methods of using the bar or tool for causing a relative shifting of vehicle springs and their suspension means whereby the strain on the parts may be temporarily relieved to facilitate the introduction of lubricant thereto.

In Figure 3 there is shown a vehicle spring construction in which the side frame member 22 of the vehicle terminates in a downwardly projecting horn 24 which is formed with a transverse bore 26. The vehicle spring 28 is arranged below the frame member and terminates in an eye 30. A spring shackle 32 is employed for suspending the spring 28 on the horn of the frame member, said shackle 95 100

including at its upper end a bolt 34 which is received rather loosely in the bore 26 of the horn and at its lower end a similar bolt 36 which is received rather loosely in the eye 30 5 of the spring.

Each shackle bolt 34 and 36 is formed with a longitudinal recess or passage 38 having radially extending discharge ports 40 opening to the circumference of the bolt. These 10 passages and discharge ports are employed for forcing grease to those parts of the shackle bolts which contact frictionally with the members in which they are mounted. The method of lubricating these shackle bolts 15 usually involves the use of well known pressure devices.

It is well known, however, that on account of the weight which rests on the shackle bolts, whereby those parts which receive the greatest 20 wear are caused to forcibly contact with the surfaces of the members in which they are received, such for instance as the upper part of the bore 26 and the lower part of the eye 30, it is difficult to cause the grease to 25 reach the parts which are mostly in need of lubrication.

By the use of our tool this strain may be temporarily relieved and this is accomplished, with respect to this particular construction, as indicated in Figure 3.

The hooked end of the bar is inserted between the side members of the shackle 32 with the hook portion 16 facing upwardly and the curved face 18' contacting with the inner 35 part of the periphery of the eye 30 of the spring.

Pressure is then applied to the tool by bearing down on the outer end of the body 10 in the direction of the arrow *a*, whereby the 40 horn 24 and spring 28 are forced apart to a slight extent, this movement being permitted by the loose mounting of the shackle bolts in the respective members. The point of the hook 16 engages the bottom surface of the 45 horn 24 and the curved face 18' slides or rolls somewhat on the eye 30 and considerable lever advantage may be obtained in this way to separate the members as shown in Figure 3.

50 This separation moves the horn 24 and spring 28 away from those parts of the shackle bolts which are ordinarily in contact and permits the grease to be extruded from the discharge passages 40 to those points 55 which receive the greatest wear and are, therefore, in most need of receiving lubrication.

Then the tool is removed by upward and outward movement and the operation is repeated at other points on the vehicle.

In the construction according to Figures 4 and 5 no shackles are employed but the eye 42 of the spring 44 is received directly on a bolt 46 carried by the horn 48 of the frame 65 member 50.

With respect to this spring construction, the tool may be inserted laterally between the rear ends of the spring and frame member, or its horn, in substantially the same position as previously referred to. The pressure is then applied in the direction of the arrow *b* in Figure 5.

The shank portion 14 is caused to engage beneath or against the lower face of the frame member 50 and the curved fulcrum face 18' is caused to engage against the upper surface of the spring 44, thus facilitating the operation of slightly spreading these members for a purpose similar to that already described.

In Figure 6 there is illustrated a type of spring construction in which the spring 52 is mounted above the axle member 54 and parallel therewith. The ends of the spring 52 are supported by spring shackles 56 suspended from posts 58 carried by the axle 54.

In using the tool with respect to this type of spring construction, the flat blade 12 is employed and is inserted between the axle 54 and the end of the spring and shackle as shown in Figure 6. Downward pressure is exerted in the direction of the arrow *c* to lift the weight carried by the spring and permit a movement of the spring and shackle bolts 60 whereby the insertion of the lubricant is permitted in the required points. In this operation the curved outer face of the blade, which we have designated by the numeral 12', is caused to ride on the upper face of the axle 54.

In the construction according to Figure 7 there is shown a spring arrangement similar to that of Figure 3 and in which the same numerals are employed to designate corresponding parts. The construction includes also a bumper member 62 which is placed so close to the ends of the frame member and spring as to cause some interference with the use of the tool in the lubricating operation.

For this reason we have shown a modified form of tool in which the handle or body portion 10' is formed with a downward offset 10" near that end carrying the fulcrum member. This offset permits the insertion of the tool behind the bumper 62 as clearly shown. The pressure is applied to the outer end of the tool in the direction of the arrow *d* for separating the members to permit proper lubrication.

Through the use of our improved tool, in any or all of the methods illustrated and described, we have greatly facilitated the operation of introducing lubricant to the spring suspending members which receive the greatest wear in use. This tool greatly reduces the amount of labor required for this operation and insures that the lubricant will reach the points which are mostly in need of lubrication.

We claim as our invention:

1. A tool for use in relieving the weight on a vehicle spring, comprising a body portion, said body portion terminating in a shank having a flat blade at its end, said blade having its point curved laterally and hooked, a fulcrum member on said blade having a convex fulcrum surface on its forward side, said convex surface being adapted to ride on one object as pressure is applied to the body portion of the tool to cause the blade to forcibly contact with another object spaced from the first object, said body portion being offset rearwardly of said fulcrum member in the same general direction as the projection of said fulcrum surface from the blade, to permit insertion of said tool between a bumper and a vehicle spring.

2. A tool for use in relieving the normal weight on a vehicle spring comprising a body portion, a shank having a curved blade, and a fulcrum member on the opposite side of the shank from the direction of curvature of its blade, said fulcrum member being of substantially right-angled form having one leg extending along said shank and the other leg extending away therefrom, the ends of said legs being connected adjacent said blade by a convex bearing surface for riding on one member of a spring assembly when the blade is caused to engage another member of the assembly, whereby the body portion may be used as a lever for slightly separating the members of the spring assembly.

35 Des Moines, Iowa, July 31, 1929.
